UNITED STATES PATENT OFFICE.

CHARLES G. TROSIEN, OF PONTIAC, MICHIGAN.

GEAR LOCK FOR AUTOMOBILES.

Application filed February 27, 1922. Serial No. 539,435.

To all whom it may concern:

Be it known that I, CHARLES G. TROSIEN, citizen of the United States, residing at Pontiac, county of Oakland, State of Michigan, have invented a certain new and useful improvement in Gear Locks for Automobiles, and declare the following to be a full, clear, and exact description of the same, such as will enable others skilled in the art to which it pertains to make and use the same, reference being had to the accompanying drawings, which form a part of this specification.

My invention relates to gear locks for automobiles and an object of my improvements is to provide a means for locking the gears in a special form of construction hereinafter distinguished.

In the drawings,—

Figure 1 is a sectional elevation of a part of a gear case and apparatus embodying my invention.

Fig. 2 is an end elevation of the same looking from the right of Fig. 1.

Fig. 3 is a sectional plan view, the section being taken on the line III—III, Fig. 2.

Fig. 4 is a partial view similar to Fig. 3, showing the parts in a different position.

Fig. 5 is a detail sectional view in elevation taken from the position indicated by the line V—V, Fig. 1.

Fig. 6 is a view similar to Fig. 4 showing a modified construction.

Fig. 7 is a detail showing two positions of the operating parts of the construction shown in Fig. 6.

Fig. 8 is a detail section on the line VIII—VIII, Fig. 6.

Fig. 9 is a perspective view of the locking rod.

Fig. 10 is a detail end view showing the actuating pin for the locking rod of Fig. 9.

Fig. 11 is a sectional detail illustrating the construction of the fork-carrying sleeve, the section being taken on the line XI—XI, Fig. 1.

Fig. 12 is a view similar to Fig. 2 showing a means of locking the parts to prevent the removal of any one of said parts.

Fig. 13 is a section on the line XIII—XIII, Fig. 12.

Fig. 14 is a view similar to Fig. 13, illustrating the modified construction shown in Fig. 6.

a is the casing for the change-speed gear; b, b are guide rods fixed horizontally

in said casing parallel to the line of movement of the gears and adjacent to said gears. c is a rod parallel to the rods b, b and located between the same. The rod c is secured at one end in one wall of the casing a and extends part way through said casing. d and d² are sleeves carrying the forks for engaging and shifting the gearing. These sleeves slide upon the rods b, b, as indicated. b² are grooves in the rods b into which pawls b³ are yieldingly pressed by springs, as shown in Fig. 5, to indicate the various positions of the gears. c² is a transverse diametral aperture through the rod c between the sleeves d and d². c³, c⁴ are balls located and adapted to travel in the slot c².

As an alternative construction, the balls may be replaced by cylindrical rods c⁵a (Fig. 6); d³ and d⁴ are grooves in the sides 75 of the sleeves d, d² adjacent to the rod c, into which the balls c³ may extend. The diameter of the balls c³ or the length of the cylindrical pieces c⁵a with their inward extensions is such that when one of said balls 80 or cylinders is entirely within the aperture c², the other is extended therefrom and engages in its respective apertures d³, d⁴ to prevent the movement of the corresponding sleeve d. In this way, only one of said 85 sleeves may be moved at one time because when one is moved the adjacent ball or cylinder is pressed into the aperture c² and forces the other of said balls or cylinders out of said aperture, engaging it in its respective groove b³ or b⁴.

The above is a known construction. To provide a locking means for this type of gearing, I bore a cylindrical aperture axially in from the inner end of the rod c to 95 join with the transverse aperture c². Into this aperture fits a locking rod e which, in the form shown in Figs. 1 to 4 inclusive, reciprocates axially to perform its function. The casing a is provided with an aperture f² through which the rod e may be inserted and adjusted to place. f is a vertically-extended rod adapted to oscillate or rotate in bearings in the casing a, its lower end being provided with a cam f² which engages the 100 outer end of the locking rod e. The upper end of the rod f is provided with a barrel lock which may be actuated by a key. When the sleeves d, d² are in neutral position of the gearing, the grooves d³, d⁴ are opposite to each other. Now if the rod f be turned to the position shown in Fig. 3, the locking 105

rod *e* is pressed forward, its chamfered end being forced between the balls *c*³, forcing said balls outward and holding them in engagement in both of the slots *d*³ and *d*⁴, so that the gearing is locked from movement. When the rod *f* is turned to the position indicated in Fig. 4, the rod *e* may be forced backward by the inward movement of one or the other of the balls *c*³, thus unlocking 10 the sleeves and gearing.

It will be observed that a rod *b* might be removed, thus unlocking the mechanism in the constructions shown in Figs. 1 to 4, inclusive. To prevent such removal, I provide apertures in the walls of the sleeves *d*, *d*² adjacent to the rod *e* which apertures, when the gearing is in its neutral position are axially in line with the apertures *c*² (Fig. 12) and place a ball *g* in each of said 15 apertures. I also provide a groove *b*⁶ (Figs. 13 and 14) in the inner wall of the rods *b*, *b*, in such position that they shall be in line with the apertures in which the balls *g* reciprocate when the gearing is in its neutral 20 position. The size of these balls is such that when the balls *c*³, *c*⁴ are pressed outward into the locking position, as above described, the balls *g*, *g* will be thereby forced part way out of their grooves and thus engage in the slots *b*⁶. In this way, the rods *b*, *b*, the sleeves *d*, *d*², and the rod *e* are all locked together and these parts, or any of them, cannot be removed.

In Figs. 6 to 10, I have illustrated a modified construction in which the cylindrical locking blocks *c*³*a*, *c*⁴*a* are substituted for the balls *c*³, and a rod *ea* having a cam *ea*³ on its inner ends is adapted to be rotated to force the block *c*³*a* outward into the locking 35 position or to permit them to be forced inward, as above described. The rod *f* is adapted to actuate the rod *ea* by means of an eccentric pin *f*²*a*, which engage in a slot *ea*² in the periphery of the rod *ea* at its 40 outer end. By turning the rod *f* to one position the mechanism is unlocked and by turning it to the other position the mechanism is locked. The two positions of the rods and the way in which the pin actuates 45 the rod *ea* is illustrated in the two views of 50 Fig. 7.

What I claim is:

1. In combination with change speed gearing having reciprocating parts and a rod *e* extending between said parts, of a lock mechanism on said rod adapted to be adjusted on said rod at will to engage said parts to lock the same from motion or to disengage said parts.

2. In a change-speed gearing having reciprocating parts, guides for said parts, a

rod extending between said parts, and an apparatus on said rod adapted to lock said parts and apparatus on said parts adapted to engage the guides therfor when the apparatus on said rod is adjusted to locking position.

3. In a change-speed gearing, reciprocating parts, a rod extending between said parts, guides for said reciprocating parts and means for binding together said rod, reciprocating parts and guides at will.

4. In a change-speed gearing having reciprocating parts and a rod *c* extending between said parts in the direction of motion of said parts and carrying an alternative locking mechanism for said parts, an actuating piece extending into a cavity in said rod, and means for operating said actuating piece whereby said alternative locking mechanism is caused to lock both of said reciprocating parts.

5. In a change-speed gearing having two reciprocating parts, a rod extending between said parts in the direction of motion of said parts and carrying an alternative locking mechanism for said parts, said rod being provided with an aperture extending in from its end in the direction of the length of said rod, a locking part extending into said aperture adapted to actuate said alternative locking mechanism to lock both of said reciprocating parts.

6. In combination with the mechanism of claim 1, a casing enclosing said parts and means extending from the outside of said casing for operating said locking part.

7. In a change-speed gearing having reciprocating parts and a rod *c* extending between said parts and carrying an alternative locking mechanism for said sleeves, an actuating piece extending into a cavity in said rod, and means for operating said actuating piece whereby said alternative locking mechanism is caused to lock both of said reciprocating parts, said reciprocating parts being provided with grooves in their walls adjacent to said rod, reciprocating parts in each of the last-named grooves, a stationary part adjacent to said wall having a groove therein, the construction and relative arrangement being such that when an alternative locking part is actuated into locking position, it shall force one of the parts in the groove in the reciprocating part into engagement in the groove in said stationary part, substantially as and for the purpose described.

In testimony whereof I sign this specification.

CHARLES G. TROSIEN.
